(57) **CLAIM**

The ornamental design for a cover for receiving a flexible conduit from a garage door sensor, as shown and described.

DESCRIPTION

FIG. 1 is a top, side, front perspective view of a cover for receiving a flexible conduit from a garage door sensor; FIG. 2 is a top, side, rear perspective view thereof; FIG. 3 is a front view thereof; FIG. 4 is a side view thereof, it being understood the other side is a mirror image thereof; FIG. 5 is a top view thereof, it being understood that the bottom is a mirror image thereof; and FIG. 6 is a perspective view thereof showing the cover for receiving a flexible conduit from a garage door sensor and the conduit in use, connected to a garage wall. The surrounding environment is shown with broken lines which form no part of the claimed design. FIGS. 1–6 use a separation and a bracket in the conduit to indicate, for ease of illustration, that the precise length of the conduit is not claimed.

1 Claim, 6 Drawing Sheets
